Primary Examiner — Vy Koenig*Assistant Examiner* — Kimberly Barnes(74) *Attorney, Agent, or Firm* — Eckert Seamans Cherin & Mellott, LLC; Nathaniel C. Wilks(57) **CLAIM**

The ornamental design for a roof anchor, as shown and described.

DESCRIPTION

FIG. 1 is an upper front right perspective view of the roof anchor;

FIG. 2 is a front elevational view thereof;

FIG. 3 is a top plan view thereof;

FIG. 4 is a left side elevational view thereof;

FIG. 5 is a rear elevational view thereof;

FIG. 6 is a right side elevational view thereof; and,

FIG. 7 is a bottom plan view thereof.

The broken lines illustrate portions of the roof anchor that form no part of the claimed design.
